DESIGN FOR A CLOCK

Shogoro Yoshida, Shitaku, Tokyo, Japan

Application June 14, 1934, Serial No. 52,181

Term of patent 7 years

To all whom it may concern:

Be it known that I, Shogoro Yoshida, a subject of the Emperor of Japan, residing at No. 12, Ueno Motokuromoncho, Shitaku, Tokyo, Japan, have invented a new, original, and ornamental Design for a Clock, of which the following is a specification, reference being had therein to the accompanying drawing, forming part thereof.

The figure is a perspective view of a clock, showing my new design.

I claim:

The ornamental design for a clock, as shown. In testimony whereof I affix my signature.

SHOGORO YOSHIDA.
